CLAIM

The ornamental design of a modular flooring tile, as shown and described.

DESCRIPTION

FIG. 1 is a top perspective view of the modular flooring tile; FIG. 2 is a top plan view of the modular flooring tile of FIG. 1;

FIG. 3 is a front elevation view of the modular flooring tile of FIG. 1;

FIG. 4 is a back elevation view of the modular flooring tile of FIG. 1;

FIG. 5 is a right side elevation view of the modular flooring tile of FIG. 1;

FIG. 6 is a left elevation view of the modular flooring tile of FIG. 1;

FIG. 7 is a bottom perspective view of the modular flooring tile of FIG. 1; and,

FIG. 8 is a bottom plan view of the modular flooring tile of FIG. 1.

The broken lines shown in the drawing Figures are meant to illustrate environment and form no part of the claimed design.

1 Claim, 5 Drawing Sheets
